PHILIP SCHWICKART, OF NEW YORK, N. Y.

VENTILATING AND LIGHTING CONSTRUCTION.

1,146,660.

Specification of Letters Patent. Patented July 13, 1915.

Application filed May 22, 1913. Serial No. 769,205.

To all whom it may concern:

Be it known that I, PHILIP SCHWICKART, a citizen of the United States, and a resident of the city of New York, borough of Brooklyn, in the county of Kings and State of New York, have invented a new and Improved Ventilating and Lighting Construction, of which the following is a full, clear, and exact description.

The invention relates to walls, skylights, sidewalks, floors, roofs and other parts of buildings and other structures, and its object is to provide a new and improved ventilating and lighting construction arranged to provide an exceedingly strong and durable structure, and to permit of quickly and accurately assembling the various parts without the employment of skilled labor.

In order to produce the desired result, use is made of side beams having spaced seats, cross bars in the form of angle irons fitting the said seats with the corners downward and the side members diverging upwardly, and building light units having their sides seated on the edges of the side members of the cross bars.

A practical embodiment of the invention is represented in the accompanying drawings forming a part of this specification, in which similar characters of reference indicate corresponding parts in all the views.

Figure 1 is a plan view of the ventilating and lighting construction with portions of the cementitious filling and some of the reinforcing rods omitted; Fig. 2 is a sectional side elevation of the same on the line 2—2 of Fig. 1; Fig. 3 is a reduced plan view of the skeleton frame for supporting the units, the reinforcing rod and the cementitious filling; Fig. 4 is an enlarged cross section of the same on the line 4—4 of Fig. 1; Fig. 5 is an enlarged sectional side elevation of a modified form of a unit; Figs. 6, 7 and 8 are side elevations of different forms of the supporting side beams of the skeleton frame; and Fig. 9 is a perspective view of a modified form of the supporting frame for the units.

The units A are supported on spaced cross bars B of a skeleton frame (see Fig. 3), having side beams C supporting the said cross bars B and resting on a suitable foundation. The cross bars B and the side beams C are preferably made of angle irons and the side beams C have their vertical members provided with triangularly shaped

seats C' in which are seated the cross bars B having their corners downward and the side members diverging in an upward direction, as will be readily understood by reference to Fig. 2. Each of the units A consists of an open frame A', preferably square, and having the lower edges of its sides A² beveled and resting on the edges of the opposite side members of adjacent cross bars B, as will be readily understood by reference to Fig. 2. The sides A² of each unit frame A' are inclined upwardly and inwardly and are provided at the outside with integral retaining lugs A³ projecting below the lower beveled edges of the sides A² and fitting onto the corresponding side members of the cross bars B so as to prevent sidewise shifting of a unit on its two supporting cross bars B. The ends A⁴ of the frame A' of a unit are inclined upwardly and inwardly, as plainly indicated in Fig. 4, and are provided with base flanges A⁵, A⁶, of which the base flange A⁵ of one frame A' abuts against the flange A⁶ of the next following unit supported on the same cross bars B. The base flange A⁵ of each unit is provided with a dovetail tongue A⁷ fitting into a correspondingly shaped groove A⁸ in the abutting base flange A⁶ of the next following unit, as plainly indicated in Fig. 1 so that the several units arranged in one row and supported by the same pair of cross bars B are connected with each other. A strengthening rib A⁹ connects integrally with the tongue A⁷, the base flange A⁵ and the corresponding end A⁴ so as to give the desired strength to the tongue A⁷, and the rib A⁹ is provided with a top notch A¹⁰ forming a seat for the reinforcing rod D extending the entire width of the structure. A reinforcing rod E is arranged centrally in the trough formed by each cross bar B, and a cementitious filling F is filled into the cavities formed by the angle iron cross bars B, the abutting flanges A⁵, A⁶ and the sides A² and ends A⁴ of the units A, to embed the reinforcing rods D and E as well as the lugs A³ and ribs A⁹, the top of the cementitious filling F being flush with the upper faces of the building light units A, as indicated in Fig. 2.

As shown in Figs. 1 and 2 one of the rows of units A is in the form of an open grate while the adjacent row of units is of the closed type, that is, is provided with lenses G. The open top unit A is provided with

intersecting tapering bars A¹¹ wider at the top than at the bottom so that the open spaces formed by the said tapering bars A¹¹, the sides A² and the ends A⁴ are gradually increasing in size from the top downward to the bottom of the unit to prevent dirt, rubbish or other extraneous matter from lodging in the said spaces thus rendering each unit practically self-cleaning. In using the structure as a grating on pavements extending over subways, cellars and the like, the open grate units insure proper ventilation of the area below the structure and at the same time the open grate units are not liable to be clogged up by extraneous matter. Each lens G in the next row of units fits into the entirely open skeleton frame A' and is supported at the bottom on an annular flange A¹² formed integral with the sides A² and the ends A⁴ of the frame A'. Each of the lenses G is fastened in place by the use of cement, putty or similar material filled into the space between the edges of the lens G and the sides A² and ends A⁴ of the units A, as plainly indicated to the left in Figs. 1 and 2.

It is understood that by the arrangement described the lenses G refract the light into the space below the building light or grating and the rays of light can also pass directly through the open work units, which also form a ventilating means for the space below the construction as above described.

It is evident that a building light or a grating can be constructed using only building light units having lenses G or only units having open skeleton frames, and hence I do not limit myself to either form of construction as the same is varied according to the use made of the construction.

As shown in Fig. 5, a grate I may be inserted instead of a lens G in the open top of the unit, the grate I resting on the flange A¹². The seats C' of the side beams C may be entirely open, as shown in Fig. 8, so as to permit of placing the cross bars B into the seats from above, but the notches C' may be provided at their upper end with converging shoulders C², as shown in Fig. 7, so as to hold the cross bars B against upward movement, it being, however, understood that in this case the cross bars be slipped into the seats C' endwise. The seats C' may also be entirely closed at the top, as indicated in Fig. 6, to hold the cross bars against upward movement, it being understood that in this case the cross bars have also to be slipped endwise into position in the seats.

Instead of using angle iron for the cross bars, the latter may be made of channel iron B' (see Fig. 9) with the side members extending upwardly for the units to rest on the opposite side members of the adjacent cross bars. In this case the side beams C'

are provided with seats corresponding to the cross section of the channel iron cross beams. The channel iron cross bars form troughs similar to the troughs formed by the angle iron cross bars for the reception of the cementitious filling. 70

The construction shown and described is very simple in construction and the several parts of the cross bars B can be placed in position on the side beams C, and then the units A can be quickly and accurately fitted onto the cross bars, after which the reinforcing rods D and E are placed in position. The cementitious filling F is poured into the troughs or cavities, to embed the reinforcing rods and at the same time lock the units in place. By setting up angle iron cross bars B in the manner described and providing the units A with inclined sides and ends, it is evident that the rays of light can readily pass into the space below the construction to properly illuminate the same. 80

Having thus described my invention, I claim as new and desire to secure by Letters Patent: 90

1. A construction of the class described, comprising side beams having V-shaped spaced seats, spaced cross bars in the form of angle irons and seated on the said seats and each having its side members extending upwardly, and units each in the form of a skeleton frame having integral sides and ends, the lower edges of the said unit sides being beveled and seated on the upper edges of the opposite members of adjacent cross bars. 95

2. A construction of the class described, comprising side beams having V-shaped spaced seats, spaced cross bars in the form of angle irons and seated on the said seats and having its side members extending upwardly, the said side beams having integral means at the said seats and engaging the upper edges of the said side members to hold the same against upward movement, and units seated on the upper edges of the opposite side members of adjacent cross bars, each unit being in the form of an open approximately rectangular skeleton frame having integral sides, ends and intersecting cross bars. 100

3. A construction of the class described, comprising side beams, spaced cross bars seated on the said side beams and each provided with upwardly extending side members, and units seated on the upper edges of the opposite members of adjacent cross bars, each unit being in the form of an open skeleton frame having integral sides, ends and intersecting cross bars, the said ends of each unit being provided with base flanges, of which the flange at one end of one unit connects with the adjacent flange of the next following unit to space the units apart in a transverse direction. 110

4. A construction of the class described, comprising side beams having V-shaped spaced seats, spaced cross bars in the form of angle irons and seated on the said side beams and each having its side members extending upwardly, rows of units each in the form of a skeleton frame having integral sides, ends and intersecting bars, the units in each row having the lower edges of their sides beveled seated on the upper edges of the opposite members of adjacent cross bars, the ends of adjacent units being spaced apart to form channels at right angles to the said cross bars, reinforcing rods in the troughs formed by the cross bars, reinforcing rods in the said channels, and a cementitious filling material in the said troughs and channels, and embedding the said reinforcing rods and engaging the sides and ends of the said units. 70
5. A construction of the class described, comprising side beams having spaced seats, cross bars in the form of angle irons fitting the said seats with the corners downward and the side members diverging upwardly, and units each in the form of a skeleton frame and having integral sides, ends and intersecting bars, the lower edges of the said sides being seated on the upper edges of the said side members of the cross bars, each unit being provided at its sides with spaced retaining lugs fitting exteriorly onto the upper faces of the said side members of the cross bars. 80
6. A construction of the class described, comprising side beams having spaced seats, cross bars in the form of angle irons fitting the said seats with the corners downward and the side members diverging upwardly, and units each in the form of a skeleton frame having sides, ends and intersecting bars forming a grate, the lower edges of the sides being seated on the upper edges of the said side members of the cross bars, each unit being provided at its ends with outwardly extending flanges provided with interlocking members, of which the interlocking member of the flange of one unit engages and interlocks with the abutting flanges of the adjacent unit. 90
7. A construction of the class described, comprising side beams having spaced seats, cross bars in the form of angle irons fitting the said seats with the corners downward and the side members diverging upwardly, and units each in the form of a skeleton frame having sides, ends and intersecting bars forming a grate, the lower edges of the sides being seated on the upper edges of the said side members of the cross bars, each unit being provided at its ends with outwardly extending flanges provided with interlocking members of which the interlocking member of the flange of one unit engages and interlocks with the abutting flanges of the adjacent unit. 100
8. A construction of the class described, comprising side beams having spaced seats, cross bars in the form of angle irons fitting the said seats with the corners downward and the side members diverging upwardly, and units each in the form of a skeleton frame having sides, ends and intersecting bars forming a grate, the lower edges of the sides being seated on the upper edges of the said side members of the cross bars, each unit being provided at the ends with outwardly extending flanges provided with interlocking members of which the interlocking member of the flange of one unit engages and interlocks with the abutting flange of the adjacent unit, and reinforcing ribs integrally connecting the flanges with the ends of the units, each rib being notched at its top to form a seat for supporting a reinforcing member. 110
9. A construction of the class described, comprising side beams, having spaced seats, cross bars in the form of angle irons fitting the said seats with the corners downward and the side members diverging upwardly, and units each in the form of a skeleton frame having sides, ends and intersecting bars forming a grate, the lower edges of the sides being seated on the upper edges of the said side members of the cross bars, the units being provided at the ends with base flanges, of which the flange of one unit abuts the corresponding base flange of the next adjacent unit. 120
10. A construction of the class described, comprising side beams having spaced seats, cross bars in the form of angle irons fitting the said seats with the corners downward and the side members diverging upwardly, and units each in the form of a skeleton frame having sides, ends and intersecting bars forming a grate, the lower edges of the sides being seated on the upper edges of the said side members of the cross bars, the units being provided at the ends with base flanges, of which the flange of one unit abuts the corresponding base flange of the next adjacent unit, one of the end flanges of each unit being provided with a dovetail notch and the other end flange being provided with a dovetail tongue fitting into the dovetail notch in the abutting flanges. 130
11. A construction of the class described, comprising spaced side beams provided with triangular cross bars in the form of angle irons seated in the said seats and having their side members diverging in an upward direction, units in the form of skeleton frames having integral sides, ends and intersecting bars forming a grate, the lower edges of the sides being beveled and seated on the opposite side members of adjacent 125

cross bars, the units being provided with integral abutting and interlocking base flanges, ribs integrally connected with the said base flanges and the ends of each unit and provided with top notches, longitudinally-extending reinforcing rods seated in the said notches, and a cementitious material filling the cavities formed by the said angle irons, the abutting flanges and the sides and ends of the said units, the said cementitious material embedding the said reinforcing rods.

12. A construction of the class described, comprising spaced side beams provided with triangular seats, cross bars in the form of angle irons seated in the said seats and having their side members diverging in an upward direction, units in the form of skeleton frames having the lower edges of their sides beveled and seated on the opposite side members of adjacent cross bars, the units being provided with integral abutting and inter-

locking base flanges, ribs integrally connected with the said base flanges and the ends of each unit and provided with top notches, 25 each unit being provided at the sides with integral retaining lugs engaging the side members of the cross bars, reinforcing cross rods in the space formed by the side members of the cross rods, longitudinally-extending reinforcing rods seated in the said notches, and a cementitious material filling the cavities formed by the said angle irons, the abutting flanges and the sides and ends of the said units, the said cementitious material embedding the said reinforcing rods. 30

In testimony whereof I have signed my name to this specification in the presence of two subscribing witnesses.

PHILIP SCHWICKART.
